SKI BOB

Dieter E. W. Kuntz, 859 Cortez St.,
Costa Mesa, Calif. 92626

Filed Sept. 29, 1970, Ser. No. 25,245

Term of patent 14 years

Int. Cl. D21—02

U.S. Cl. D34—15

FIG. 1 is a top perspective view of a ski bob showing my new design;

FIG. 2 is a side elevational view of FIG. 1 on an enlarged scale as taken from lines 2—2;

FIG. 3 is a side elevational view of FIG. 1 on an enlarged scale as taken from lines 3—3;

FIG. 4 is a fragmentary top plan view of FIG. 3 as taken from lines 4—4;

FIG. 5 is a fragmentary rear elevational view of FIG. 3 as taken from line 5—5;

FIG. 6 is a fragmentary side elevational view of FIG. 1 on an enlarged scale as taken from line 6—6;

FIG. 7 is a rear elevational view of FIG. 6 as taken from line 7—7.

I claim:

The design for a ski bob, substantially as shown and described.
